UNITED STATES PATENT OFFICE

JAMES P. BARTON, OF SPRINGFIELD, MASSACHUSETTS, ASSIGNOR TO WESTINGHOUSE ELECTRIC & MANUFACTURING COMPANY, A CORPORATION OF PENNSYLVANIA

RADIO RECEIVING SYSTEM

Application filed March 5, 1930. Serial No. 433,294.

My invention relates to radio receiving systems and it has particular relation to systems of the type wherein a loop-antenna is utilized for both the reception and the radiation of energy.

When a loop-antenna is a constituent part of a combined transmitting and receiving system such as, for example, an end-to-end communication system for railway trains of the type disclosed in the copending application of H. C. Forbes, Serial No. 267,585, filed April 5, 1928, and assigned to the Westinghouse Electric & Manufacturing Company, it is highly desirable that means shall be provided for preventing injury to anyone who might happen to come in contact with the loop when signals are being transmitted.

It is also necessary to provide means for preventing the generation of undesirable oscillations in the receiving apparatus when it is connected to the loop and, for this purpose, a neutralizing network analogous to that disclosed in the patent to Rice, 1,334,118, is advantageous.

If the Rice circuit is used exactly as disclosed in the patent, however, it necessitates an additional connection between the center of the loop and the cathodes of the thermionic tubes in the receiving amplifier and greatly complicates the switching apparatus required for changing the system from the receiving to the transmitting condition.

It is, accordingly, an object of my invention to provide, in a combined radio transmitting and receiving system wherein a single loop-antenna is utilized for both the transmission and the reception of signals, means for preventing injury to anyone who accidentally makes contact with the loop during the transmission of signals.

Another object of my invention is to provide, in a system of the type referred to, means for the prevention of undesired oscillations in the signal-receiving apparatus.

In applying my invention to a railway

signaling system, of the type disclosed in the aforementioned application of H. C. Forbes, I provide a rigid loop-antenna one end of which is permanently connected to ground through the metallic portions of the engine or car upon which it is mounted. Inasmuch as the cathodes of the thermionic tubes in both the transmitting and receiving portions of the system are also connected to ground there is no necessity for disturbing the ground connection of the loop when shifting from the transmitting to the receiving condition. I connect the other terminal of the loop to a single switching device, therefore, whereby the loop can be associated with the transmitter or with the receiver, at will.

When the switching device is in the receiving position the ungrounded terminal of the loop is connected, through a variable tuning condenser, to one terminal of an input inductor included between the grid and cathode of the first thermionic tube in the receiving amplifier.

Neutralization against oscillation in the receiving amplifier is provided for by connecting a circuit including an inductor and a variable condenser between the plate of the first thermionic tube and the cathode thereof, and by so disposing the said inductor with respect to the input inductor of the tube that the inductive feedback is in the proper sense.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with the accompanying drawing.

The single figure of the drawing is a diagrammatic view of a portion of a radio sig-

naling system comprising a preferred embodiment of my invention.

Inasmuch as my invention relates particularly to the final, or power-amplifier, 5 stage of a radio transmitter, the initial stage of a receiving amplifier and the manner in which the said stages are selectively associated with a loop-antenna, I have not illustrated other portions of the system. It is 10 to be clearly understood, however, that the transmitter may comprise any of the conventional circuits whereby signal-modulated high-frequency energy shall be delivered to the loop-antenna, for radiation therefrom, 15 and that the receiving amplifier may comprise the usual demodulator and audio-frequency amplifier stages adapted to deliver energy to a loud-speaker or other indicating device.

20 The apparatus shown in the drawing comprises a loop antenna 1 one end of which is connected to ground through the metallic portions and the running-gear 2 of a railway-car (not shown) upon which it is mounted. The other end of the loop leads to a switching device 3 whereby it may be selectively associated with the output circuit of a thermionic tube 4 in the transmitting portion of the system, or, through 25 a tuning condenser 5, with one end of an input inductor 12 connected between the grid and cathode of a thermionic tube 7 comprised in the receiving amplifier.

30 The cathodes of the thermionic tubes comprised in the transmitting and receiving portions of the system may be energized in parallel from a common source 8 and a common source of plate potential 10 may also be used. By reason of the fact that the 35 transmitting tubes require very much higher plate voltages than the receiving tubes it is customary, however, to supply them with potential from a motor-generator.

40 In order to prevent the generation of oscillations in the receiving portion of the system, when the loop and the input circuit are tuned to the frequency of the desired signal, a neutralizing network is provided, the said network being constituted 45 by a feed-back condenser 11 and an inductor 6 serially connected between the plate of the tube 7 and the cathode thereof. The neutralizing inductor is disposed in inductive relation to the input inductor 12 and the 50 direction of the windings thereof is so chosen that the potentials induced therefrom across the said input inductor are opposite in phase to the potentials arising therein by reason of feed-back through the plate-grid 55 capacity of the tube.

60 The input inductor and the neutralizing inductor may be constituted by a bi-filar winding or they may be the halves of a continuous winding having a mid-tap connected to the cathode of the tube, it being

primarily essential that there shall be a high value of coupling between the said inductors if the system is to remain free from oscillations over a reasonable tuning range.

70 The entire receiving amplifier is, preferably, enclosed within a grounded metallic shield (not shown) in order to prevent the apparatus from being influenced by signals other than those collected by the loop.

75 In the operation of my improved radio receiving system, the input circuit, constituted by the loop-tuning condenser, the input inductor and the loop connected in series, is tuned by the said condenser to the carrier-frequency at which reception is desired. Inasmuch as the inductance of the loop is, preferably, made equal to the inductance of the input inductor substantially 80 one half of the available signal potential appears across the input terminals of the thermionic tube.

85 It will be apparent, from a consideration of the foregoing description of my improved signaling system, that dangerously high potentials are prevented, by the ground connection, from being developed across the loop-antenna during the transmission of signals. This feature is decidedly advantageous 90 in that it prevents injury to the trainmen should they accidentally make contact with the loop when it is energized.

95 Furthermore, my invention obviates the necessity of providing the loop with a center-connection, such as is necessitated if the Rice circuit is employed exactly as it is shown in the patent, and greatly simplifies the problem of shifting the loop from the transmitting to the receiving condition.

100 Although I have shown and described a specific embodiment of my invention, I am fully aware that many modifications thereof are possible. My invention, therefore, is not to be restricted except insofar as is necessitated by the prior art and by the spirit of 105 the appended claims.

110 I claim as my invention:

115 1. In a signaling system, a thermionic amplifier having a cathode, a control-electrode and an anode, an input inductor connected between the control-electrode and the cathode, a loop antenna one terminal of which is connected to the cathode and the other terminal of which is connected, through a tuning condenser, to the control-electrode, and a feed-back inductor and a condenser serially connected between said anode and said cathode, said feed-back inductor and said input conductor being inductively coupled in the sense to oppose the 120 generation of oscillations in said amplifier.

125 2. In a signaling system, a loop-antenna constituted by a single turn, a thermionic receiving amplifier having a cathode, a control-electrode and an anode, an input in- 130

ductor connected between said control-electrode and said cathode, a connection including a tuning condenser between one terminal of the loop-antenna and the control-electrode, a connection between the other terminal of the loop-antenna and the cathode, and means connected between the anode and the cathode for preventing the generation of oscillations in said amplifier.

10 In testimony whereof, I have hereunto subscribed my name this 20th day of February, 1930.

JAMES P. BARTON.
